(57) **CLAIM**

The ornamental design for a plasma outlet liner, as shown and described.

DESCRIPTION

FIG. 1 is an isometric top view of a plasma outlet liner showing our new design.

FIG. 2 is an isometric bottom view thereof.

FIG. 3 is a top plan view thereof.

FIG. 4 is a side elevational view thereof, with the opposite side being a mirror image thereof;

FIG. 5 is a bottom plan view thereof.

FIG. 6 is an end elevational view thereof, with the other end being a mirror image thereof;

FIG. 7 is a cross-sectional view thereof taken along lines 7-7 of FIG. 6; and,

FIG. 8 is a cross-sectional view thereof taken along lines 8-8 of FIG. 5.
